TREATMENT OF TAR

Arthur H. Radasch, Bloomfield, and Wilfred M. Bywater, Weehawken, N. J., assignors to The Barrett Company, New York, N. Y., a corporation of New Jersey

Application March 21, 1934, Serial No. 716,698
In Canada July 15, 1933

24 Claims. (Cl. 260—154)

This invention relates to an improved method of treating liquid hydrocarbon material such as coal tar to recover tar acids from it in the form of carbolates. The tar or other material is heated above its initial boiling point and flashed, vapors are separated from the non-volatilized tar-acid-containing residue and tar acids are distilled from this residue and recovered as carbolite by extraction of the tar acids from the vapors. By "tar acids" we mean the volatilizable constituents of tar which form salts with strong alkalies, more particularly, the phenols, such as phenol, cresols, and cresylic acids of commerce or their components. This invention includes both the method and apparatus for carrying it out.

More particularly, the invention relates to a process of flashing tar or other hydrocarbon material in which part but not all of the tar acids are vaporized by flashing, tar acids are separated from non-acid constituents in the vapor phase by alkaline extraction of the flashed vapors, and vapors remaining after the alkaline extraction are then used in whole or in part in the inert gas distillation of tar acids from the residue from the flashing operation.

The process of this invention thus includes two distilling steps, viz. a primary distillation, which is preferably carried out in a pipe-coil still by heating the tar above its initial boiling point, flashing it and separating the flashed vapors from the undistilled residue, and a secondary distillation in which tar acids are distilled from the residue resulting from the primary distillation. Inert gases which preferably include vapors of non-acid or neutral oil constituents are employed in the secondary distillation.

The process of the present invention is applicable to the treatment of tars such as coke-oven tars, gas-retort tars, vertical-retort tars, and low-temperature tars and other tar-acid and neutral-oil-containing hydrocarbon materials such as coal tar distillates or distillation residues. It may be applied to the treatment of raw moisture-containing tar or stripped tar, etc., or to the separate treatment of tar fractions such as the heavy tar from the collector main of a coke-oven plant or the light tar or tarry oil from the condensers of such a plant. It may be applied to the treatment of mixtures containing coal tar, etc. The invention will be described more particularly as applied to the treatment of coke-oven tar.

In the primary distillation or flashing opera-

tion of this invention, the tar is heated above its initial boiling point and then flashed into a vapor-separating chamber. The vapors of lower boiling constituents, which are vaporized by the self-contained heat of the tar at the temperature of flashing, are collected separately from the undistilled residue. The hot residue is then subjected to inert gas distillation in which tar acids are volatilized from the residue. The heat for the distillation is preferably supplied by the self-contained heat of the residue, although additional heat may be applied.

The inert gases used in this secondary distillation comprise gases which are inert both to tar acids and to caustic and which serve as a carrier for the tar-acid vapors. "Gas" is used in a broad sense to include fixed gases such as nitrogen and condensable vapors such as steam and oil vapors. The gas introduced into the still includes vapors of neutral oils which repress or minimize the vaporization of neutral oils of the same boiling range from the tar in the still. To the extent that the vaporization of neutral oils is repressed, the secondary distillation is selective, and tar acids are distilled from the residue without the distillation of the corresponding amount of neutral oils. The heat required for the distillation of the tar acids is thus less than that required by the ordinary methods of distillation in which neutral oils of the same boiling range as the tar acids are necessarily vaporized in order to distill off the tar acids.

An alkaline reagent is brought into contact with the gases and vapors from the inert gas distillation to extract tar-acid vapors and thus separate them from the vapors of non-acid constituents. Tar acids are thus extracted in the vapor phase and the carbolite formed separates from the vapors.

The temperature and concentration of the caustic employed for the vapor phase extraction of the tar acids may be so regulated as to effect removal of the tar-acid vapors without substantial condensation of neutral oils in the caustic extractor as a separate oil layer; ordinarily, however, some neutral oil will dissolve in and be removed with the carbolite. If the gases and vapors resulting from the inert gas distillation are cooled, oils will be condensed which may be separately collected. If the gases and vapors from the still are cooled before they enter the caustic extractor, tar-acid oils will be condensed from them. If they are cooled after tar-acid vapors have been separated in the caustic tower,

neutral oils or oils of low tar-acid content will be obtained.

The vapors from the flashing operation may be similarly treated with an alkaline reagent for the recovery as carbolate of the contained tar acids. The vapors (chiefly of non-acid constituents) remaining after this extraction may advantageously be employed as part of the inert gases used in the distillation of the residue from the flashing operation.

If the vapors from the flashing operation leave the vapor-separating chamber at a temperature above 200° C. it may be advisable to cool them to this temperature or below before bringing them into contact with the caustic solution in order to prevent the vaporization of too much water from the caustic and the production of a solution so concentrated as to be difficult to handle. Instead of cooling the vapors before they enter the caustic tower, the concentration and temperature of the caustic may be so regulated as to effect condensation of neutral oils in the caustic extractor simultaneously with the extraction of the tar-acid vapors.

Both the caustic extractor employed for extracting the gases and vapors from the secondary distillation and the caustic extractor employed for extracting the vapors from the flashing operation may be operated in a similar manner, i. e. with or without simultaneous condensation of neutral oils or each may be operated differently. Furthermore, the caustic extractions can be carried out either as batch operations or as continuous operations with gradual additions of fresh caustic and gradual withdrawal of carbolate from the alkaline liquid; both extractions may be operated alike in this respect or differently.

The two tar-acid extraction processes may be carried on independently of each other, using separate caustic feeds to each extractor and collecting separate carbolate fractions. As an alternative method, the same caustic may be employed for extracting tar acids from the two gas streams successively, feeding fresh caustic into one extractor in excess and then employing the unsaturated solution in the other extractor. As a further alternative, the carbolate from both extractions may run to a common receiver and blend therein with the caustic used for the extraction. It is desirable to bring a large volume of caustic into contact with the gases and thus effect a relatively complete absorption of the tar acids from the gases. This is conveniently done by repeatedly recirculating a portion of the caustic-carbolate mixture formed. If the same caustic solution is used in both caustic extractors, the evaporation of water from the solution or condensation of vapors from the gases in one of the caustic extractors may be offset by opposite conditions in the other extractor.

Inert gases may be generated during the treatment of tar owing both to decomposition of the tar and to the vaporization of moisture present in the tar. By providing a vent for the excess gases the apparatus of the inert-gas or secondary distillation will be operated at constant, approximately atmospheric pressure. This secondary distillation is advantageously carried out at atmospheric pressure, although pressures above or below atmospheric pressure will be employed, if desirable, by providing suitable valves and means for removal of material. Likewise, the flashing operation, although advantageously carried out at atmospheric pressure may be operated at pressures higher or lower than atmospheric. Inert

gases such as steam, nitrogen (preferably heated), etc., may be introduced either into the primary or into the secondary distilling system if desirable, to aid in the distillation.

Ordinarily the residue from the primary distillation will be at a sufficiently high temperature to permit the desired distillation of tar acids by the gases in the secondary distillation without further addition of heat; however, additional heat may be supplied either to the residue or to the gases, if necessary or desirable. According to the preferred method of operation, all of the heat required for the operation is supplied to the tar in a tar heater before the tar is flashed. The heater may be an ordinary direct-fired heater or any other suitable type of heater may be employed such as a heat interchanger in which steam or hot oil, etc. is employed for heating the tar. The waste flue gases from a coke-oven battery or gas-retort plant, etc. or from a tar still may be used for the heating.

By regulating the temperature and rate of supply of the gases, etc., the vaporization of the tar acids from the residue from the flashing operation may be carried to the point where the residue is practically completely stripped or nearly stripped of tar acids, or to the point where chiefly the lower boiling acids, for example, phenol and cresols, are removed and recovered. A partial removal of the more readily vaporizable tar acids can be effected with the removal of but a small quantity of the higher boiling and more difficultly removable acids. By controlling the flashing operation so that the greater portion of the lower boiling tar acids are vaporized and then selectively distilling the lower boiling tar acids from the residue, a high percentage of the lower boiling tar acids can be recovered as carbolate relatively free from higher boiling acids.

According to a preferred method of carrying out the process, the inert gases employed in the secondary distillation comprise at least a portion of the vapors remaining after the extraction of the vapors produced during the primary distillation. These extracted vapors may be blended with extracted gases and vapors from the secondary distillation and the mixture employed for the secondary distillation. According to the preferred method of operation, the inert gases employed in the process are produced within the process and the addition of steam or nitrogen or other inert gases from some other source is unnecessary.

According to one preferred method of operation, the extracted vapors from the flashing operation are all introduced into the still used for the secondary distillation without the addition of other inert gases. The gases and vapors resulting from the secondary distillation after tar-acid extraction are subjected to total condensation to condense oils and the remaining non-condensable gases are bled to the atmosphere or otherwise treated. As an alternative method of operation, part of the extracted vapors resulting from the secondary distillation are blended with all or a part of the extracted vapors flashed from the tar and used in the inert gas distillation and the balance of the gases and vapors from the secondary distillation are passed through a total condenser and then vented to the atmosphere or otherwise treated. Part or all of the extracted vapors from the flashing operation may be blended with part or all of the gases from the secondary distillation before these gases and vapors pass through the caustic extractor, if desirable. In

any case, the extracted vapors from the flashing operation may be subjected to cooling to condense neutral oils before being used in the inert gas distillation. The uncondensed vapors may be 5 blended with the gases and vapors from the secondary distillation before or after the latter have passed through the caustic extractor. If blended with these gases and vapors before passing through the caustic extractor, they may be blended 10 before or after the gases from the secondary distillation have been cooled to separate tar-acid oils. If blended with these gases and vapors after caustic extraction, they may be blended with them either before or after regulated cooling to 15 condense part of the neutral-oil constituents. Gases and vapors from either distillation which are not further used in the secondary distillation are vented to the atmosphere or otherwise disposed of. The vented gases are advantageously 20 cooled to recover their oil content before discharging the non-condensable gas to the atmosphere.

Although the primary distillation of this invention is preferably a pipe coil distillation with 25 flashing of the heated tar in a vapor-separating chamber, other methods of distillation may be employed that result in a continuous production of vapors and preferably a continuous production of residue also, although the withdrawal of residue 30 due from the still may be intermittent.

The invention will be further described in connection with the accompanying drawings which show in a more or less diagrammatic manner apparatus suitable for carrying out the process 35 of the invention but it is intended and is to be understood that the invention is not limited thereto.

Fig. 1 shows a pipe coil still connected with two caustic extractors and means for subjecting 40 the residue from the vapor box of the still to the inert gas distillation of this invention;

Fig. 2 shows a modified arrangement of tar acid extraction apparatus;

Fig. 3 is a modification of the apparatus shown 45 in Fig. 1 equipped with means for the condensation of separate neutral oil fractions;

Fig. 4 shows a pipe coil still as in Fig. 1 and two caustic extractors but with a different arrangement of the pipe coil still and the still for treating 50 the residue; and

Fig. 5 shows a modification in which acid oils are condensed.

In Fig. 1 an ordinary tar heater is shown at 1. The vapor box 2 is of the type usually employed 55 in connection with a pipe coil still. The residue from the primary distillation is drawn off from the vapor box 2 into the secondary still 3 where it is subjected to distillation by contact with an inert gas. Caustic extractors are shown at 4 and 60 5. Tar acids flashed from the tar in the vapor-separating chamber 2 are extracted in the vapor phase in the caustic extractor 4, and tar acids distilled from the residue in the still 3 during the inert gas distillation are extracted in the vapor phase in extractor 5.

The caustic extractors may advantageously be 65 towers packed with baffling means, such as steel screening, over which trickles the caustic-carbolic solution introduced through sprays at the top.

Both extractors may be operated in the same 70 general manner, although since the gases and vapors passing through the caustic extractor 5 usually contain a higher percentage of steam than those passing through the caustic extractor 4,

the temperature conditions and concentration of caustic, etc. may be different. In general, it is advisable to recycle through each caustic extractor a portion of the carbolic formed in it and blend it with a small amount of fresh caustic in order that there will be a large surface of liquid exposed to the action of the gases and vapors. For this purpose a portion of the caustic from the caustic extractor 4 is withdrawn through the pipe 6 and recirculated by the pump 7 through 10 the heat interchanger 8 and sprayed into the caustic extractor through the sprays 9. Fresh caustic is admitted preferably continuously, through the pipe 10. Similar apparatus is provided for recirculating carbolic through the 15 caustic extractor 5. Carbolic from the caustic extractor 4 is drawn off into the receiver 11 and from the extractor 5 into the receiver 12. If fresh caustic is continuously added to the extractors the carbolic formed is preferably drawn 20 off continuously; if the caustic is added batch-wise, the carbolic is preferable removed batch-wise.

The tar enters the system through the pipe 13. It is heated in the tar heater 1 and then flashed in 25 the vapor box 2. Steam and the vapors of lower boiling constituents of the tar pass from the vapor box through the line 15 into the caustic extractor 4. Here tar acids are extracted with caustic or other suitable alkaline reagent. The resulting 30 gases include vapors of neutral oils from which a large part or all of the tar-acid vapors have been removed; they pass through the line 16 into the bottom of the still 3.

Hot residue from the vapor box passes through 35 the line 17 into the still 3 and is distributed by the nozzles 18 over baffling means in the still. Gases from the still which include tar-acid and neutral oil vapors pass through the line 19 into the bottom of the caustic extractor 5. The gases 40 which leave the caustic extractor 5 include vapors of neutral oils from which a large part or all of the tar-acid vapors have been removed. They pass through the main 20 into the bottom of the secondary still 3. Gases from the extractor 4 45 which include vapors of neutral oil flashed from the tar in the primary distillation enter the still 3 through the line 16. A blower 21 is provided to cause circulation of the gases and vapors through the cycle of the still 3 and the caustic extractor 5. 50

Instead of combining the steam and neutral-oil vapors from the flashing operation with the recycled gases ahead of the blower, they may be combined with the recycled gases after they have passed through the blower if desired.

In order to provide for the elimination from the system of excess inert gases which include steam generated from water present in the tar, a portion of the recirculated gases is vented through a bleed provided at 22, and a condenser 23 is shown for condensing neutral oils and steam from the gases bled from the system. A decanter 24 is provided for collecting the condensate and separating the neutral oils from water. With the bleed located as shown in the drawings, all of the 60 gases from the caustic extractor 4 enter the still 3 and only a portion of the gases and vapors of neutral oils from the caustic extractor 5 pass through the still. A portion of the gases and vapors which leave the caustic extractor 5 are bled 65 from the system and are not recycled through the still 3. The residue from the secondary distillation in the still 3 is drawn off through the line 25 and collected in the receiver 26.

The heating of the tar in the tar heater may be 70

so regulated that the vapors which pass off from the vapor box include vapors of tar acids of a more or less definite boiling range so that the carbolate collected in the receiver 11 will include the tar acids of this boiling range. Or the primary distillation may be controlled so that the tar acids in the residue from the flashing operation include tar acids of a particular boiling range, which is a higher boiling range than that of tar acids that are flashed in the vapor box. Or the inert gas distillation in the still 3 may be so controlled, by regulating the rate at which the gases are circulated through the still 3, as to vaporize a greater or less percentage of the higher boiling tar acids from the residue in this still 3 together with most of the lower boiling tar acids present left in this residue after the flashing operation. In this manner, the composition of the carbolate collected in the receiver 12 may to some extent be controlled.

Coal tar varies not only in the percentage of its tar-acid content but also in the nature of the tar acids which it contains. With different tars different temperature conditions should prevail in order to produce particular results. However, in general, if coke-oven tar is heated in a tar heater sufficiently so that upon flashing the resultant vapors will be at a temperature of say 175° C. and then flashed, the tar acids in the carbolate obtained in the receiver 11 may comprise a higher percentage of phenol than the tar acids in the carbolate in receiver 12. The temperature to which the tar should be heated to obtain this vapor temperature will be around 25° C. higher, i. e. 200° C.

Fig. 2 shows an arrangement of apparatus especially adapted for obtaining two fractions of carbolate, one containing the major portion of phenol and the other containing higher phenols. The arrangement shown in this figure makes possible an improved fractionation to obtain a phenol fraction especially low in the higher phenols.

In this figure the legend 101 designates a pipe coil tar heater into which tar may be pumped at 102. Tar leaves the heater 101 by means of a pipe 103 and is passed into a vapor separating chamber 104.

The vapor separating chamber 104 is provided with a reflux column 105 of any suitable type, such as a baffle tower, a packed tower, or a bell and tray tower. The tower is provided with a liquid inlet 106 for introducing reflux liquid, and a liquid outlet 107 having a valve 108 for the removal of reflux residue from the base of the reflux column. At or near the top of the column is provided a vapor conduit 109 for the passage of vapors from the reflux column to a caustic extractor or phenol absorber 110.

The phenol absorber 110 may be of any suitable type, such as described in connection with Fig. 1, for example a packed tower. It is adapted for the passage of vapor up therethrough in counter current to and in intimate contact with a stream of sodium hydroxide solution. The tower 110 has a caustic inlet 111 at or near the top thereof and an outlet 112 for conducting carbolate to a suitable receiver 113. The withdrawal of carbolate through conduit 112 may be controlled by a valve 114. It is desired to recirculate caustic which has been used for extraction, it may be withdrawn through recirculating line 115 by means of pump 116 and reintroduced into the caustic inlet 111.

The phenol absorber 110 has a vapor outlet 117 for the removal of extracted neutral oil vapors

and for their passage to vapor line 118 to be hereinafter described. A suitable bleeder 119 and condenser 120 may be provided for condensing a portion of the oil vapors drawn off through outlet line 117. Oils thus condensed may be collected in a receiver 121 and employed as reflux liquid in the tower 105. A return pipe line 122 and pump 123 are shown for this purpose.

The vapor separating chamber or flash box 104 is provided with a liquid draw-off 124 for removing residue from the first step of the distillation. This draw-off is connected to a spray head 125 at the top of a tower 126 which may be of the packed type or other contact type of tower adapted for the passage of a liquid and gas in countercurrent relation therethrough.

The tower 126 has a draw-off 127 for removing liquid residue and has at the end adjacent the liquid inlet a conduit 128 for the removal of gases and vapors and for conducting them to a second phenol absorber 129 of type similar to or different from phenol absorber 110. This absorber is provided with a caustic inlet 130 and a draw-off 131 for carbolate for conducting it to a receiver 132. Recirculating line 133 and pump 134 are provided for the recirculation of caustic and carbolate where desired. At or near the top of the tower there is provided a vapor outlet conduit 118 for conducting vapors and gases from the caustic tower back to the extracting tower 126, thus providing a closed circuit between the vapor extraction tower 126 and the phenol absorption tower 129. A blower 135 may be provided for impelling the gases and vapors through this circuit.

This apparatus is capable of varied operation. However, the following description is given as illustrative of the methods which may be employed for obtaining a plurality of phenolate or carbolate fractions from tar-acid-containing tar by means of this process.

Crude coke oven tar containing for example around 3% of tar acids is introduced at 102 into the tar heater 101 and is heated to a temperature of around 275° C.

At this temperature the tar leaves the heater and enters the vapor separating chamber or flash box 104 where a portion of the volatile constituents are vaporized and pass up through the reflux column 105. Residue is withdrawn through draw-off 124. A suitable quantity of reflux liquid is introduced at 106 so that the vapors in passing up through the tower are gradually cooled to a temperature of around 175° C. Because of the presence of lower boiling oils as well as steam from the water content of ordinary tar this temperature is high enough to maintain phenol, which has a boiling point of 182-183° C., in vapor form. The residue from the refluxing may be withdrawn at 107 at a temperature around 235° C. for example.

Oil bled from the line 117 may be employed as this reflux liquid. When such a liquid is employed, it also undergoes a rectification in its passage down through the tower. Reflux residue 65 may be withdrawn from the rectifying column 105 by means of outlet 107 and collected as a separate tar-acid-containing oil, or by closing valve 108 this residue may be permitted to overflow into the vapor separating chamber 104 and 70 may then be collected together with the residue from the tar distillation and may be withdrawn together therewith to the tower 126 for the removal of contained higher boiling tar acids.

Alternatively reflux may be supplied by use of 75

a cooling coil in the upper part of the column 105; a cooling medium is circulated in this coil to effect partial condensation of vapors in the tower, the condensate flowing downward counter-current to the ascending vapors.

By the above rectification higher boiling phenols are fractionally removed from the gas stream, the gases and vapors entering the tower 110 are composed primarily of low boiling oils, 10 and the phenols contained are low boiling phenols, for instance the oil (which is here in vapor form) may have a boiling range of 115° to 200° C. and may also contain some water. With the vapors entering the phenol absorber 15 110 at a temperature around 175° C. such vapors will constitute around 2 to 6% of the total tar and may contain on the average from 15-35% of tar acids based on the oil. Efficient extraction of these tar acids from the vapors may be obtained in the tower 110 and these tar acids, about 20 50% of which, for example, may be phenol, may be withdrawn and collected in receiver 113.

The dephenolized or extracted vapors are then withdrawn at 117 and passed to the secondary 25 distillation tower 126. Prior to their introduction into this tower they may be partly cooled to condense a portion of the oils therefrom, if desired, but preferably they are maintained at substantially the temperature they left the phenol 30 absorber, around 165-175° C., and the bleeder 119 and condenser 120 are provided for removing a portion of the oils as condensate and preventing building up of pressure in the system. A portion of this oil condensate may then be returned 35 to the reflux column 105 to serve as reflux liquid.

Residue from vapor separating chamber 104 passes without substantial loss of temperature into the tower 126 where it is brought into intimate contact with the gases and vapors passing 40 up through the tower. This results in the removal from the tar residue of a substantial proportion of the remaining volatile tar-acid constituents.

Where, under the conditions of operation described, reflux liquid is separately withdrawn 45 from tower 105, the residue entering the tower 126 will be a pitch or partly distilled tar amounting to around 85% of the total tar distilled. In this tower 126, for example, about 1% or more 50 of the original tar may be removed as tar acids from the pitch residue by the circulation of the vapors through the tower.

The gases containing these tar-acid vapors, principally tar acids of higher molecular weight 55 than phenol, pass through phenol absorption tower 129 where tar acids are removed and collected as phenolates in receiver 132. The gases and vapors substantially denuded of their tar-acid content in tower 129 are reintroduced to 60 tower 126 after passing through the line 118 to the blower 135. By this method of recirculation the removal of neutral oils from the residue introduced into tower 126 is inhibited because of the fact that the vapors brought into contact 65 therewith comprise substantial amounts of vapors of neutral oils. The heat of the residue it-self serves to supply the requisite heat of vaporization to the tar acids and thus promotes the separation. Since the gases and vapors entering 70 the extractor tower 126 are substantially free from or low in tar acids, there is substantially no or at most a relatively low partial pressure of tar acids to inhibit their vaporization and they are thus rapidly vaporized and carried off in the 75 gas stream.

Fig. 3 is a modification of the apparatus shown in Fig. 1 and includes separate condensing means for removal of neutral oil from the vapors flashed from the vapor box after the extraction of tar acids and the removal of neutral oil from the 5 vapors from the secondary still 3a after the extraction of tar acids. The tar is heated in the tar heater 1a and flashed in the vapor box 2a. The residue from the flashing operation flows off to the still 3a by gravity. The vapors from the vapor box pass first through the caustic tower 4a and then through the condenser 30 where they are partially cooled and a portion of the neutral oil is condensed. The cooling in the condenser 30 may be regulated to condense 10 any desired fraction of the neutral oil vapors, but in no case are the vapors cooled below the dewpoint of the gases for steam.

The tar acid extraction in the caustic extractor 4a is preferably so regulated that there is substantially no condensation of neutral oils. A portion of the carbolite formed in the extractor is recirculated through the heat interchanger 8a and sprayed into the gases and vapors in the caustic extractor through the sprays 9a. Excess carbolite is drawn off into the storage tank 11a. Fresh caustic is added at any suitable point in the cycle as through the pipe 10a.

The gases and vapors which pass off from the condenser 30 contain steam and neutral oils of 20 low boiling range. They pass through the pipe 16a into the still 3a.

The gases and vapors from the still 3a pass first through the caustic extractor 5a and then through the condenser 31. In the condenser 31 the cooling of the gases is regulated to condense 25 neutral oils of any desired boiling range. The extraction of tar acids from the gases and vapors in the caustic extractor is preferably so regulated that there is no condensation of neutral oils. Caustic is recirculated as described in connection 30 with the caustic extractor 4a of Fig. 3 and excess carbolite is drawn off into the storage tank 12a. The gases and vapors from the condenser 31 are preferably blended with the gases and vapors 35 from the condenser 30 before reentering the still 3a. Means may be provided for separately introducing the two gas streams into the still 3a, if desirable.

Neutral oils are drawn off from the condenser 30 into the oil storage tank 32 and neutral oils from the condenser 31 are drawn off into the storage tank 33. The condensers 30 and 31 may be of any desirable type. They may be heat interchangers in which tar or water is used as the 40 cooling medium. The tar may be preheated by heat interchange with the hot gases and vapors before entering the tar heater 1a. Direct contact condensers may be employed in which case water may be used as the cooling medium or oil which has been condensed from the gases may be 45 cooled and sprayed into the gases and vapors to effect further condensation of oil. Rectifiers may be used where desirable. Fractional condensing means may be employed to collect two or more 50 cuts.

Fig. 3 shows condensers for removing neutral 55 oils from both gas streams. If desirable, only one condenser may be employed for removing neutral oil from one of the gas streams, i. e. either from the gases and vapors from the flashing operation or from the inert gas distillation and the other gas stream will then pass directly 60 from the caustic extractor to the still 3a.

The apparatus of Fig. 4 shows means for blending gases resulting from the vapor phase extraction of tar acids from the vapors from the flashing operation with the gases and vapors from the inert gas distillation before they are extracted.

The vapors which separate from the residue in the vapor box 2c pass over through the main 15c into the extractor 4c where they are brought into direct and intimate contact with an alkaline reagent capable of extracting the tar acids.

The neutral-oil vapors remaining after the caustic extraction escape from the extractor 4c through the line 16c. They are eventually, at least in part, used in the inert gas distillation of the residue from the flashing operation in the secondary still 3c, but according to the specific example shown in Fig. 4 they are first blended with the gases and vapors coming from this still and again scrubbed with caustic in the extractor 5c before entering the still.

The residue from the vapor box 2c is subjected to further distillation in the still 3c in an atmosphere of inert gases which includes vapors of neutral oils some of which are vaporized from the tar in the vapor box 2c and some of which are vaporized in the still 3c and recirculated through the caustic tower 5c. The gases and vapors from this secondary distillation leave the still 3c through the main 19c and are combined with vapors from the caustic extractor 4c and the combined gases pass by the main 40 into the caustic extractor 5c. Carbolate formed is drawn off into the storage tank 12c. Tar acids combine with the caustic in the extractor and the remaining gases which include vapors of neutral oils which escape from the caustic extractor are recycled through the still 3c by means of the blower 21c and the mains 20c and 41.

The blower for circulating the gases and vapors through the dephenolizer and caustic extractor is advantageously located in the line 20c by which the gases and vapors are returned to the still 3c. The blower may, however, be located in the main 40 or elsewhere, as desired.

Neutral oils may be condensed from the system where and as desired, for example in either or both caustic extractors or in coolers provided for this purpose. The recycled inert gases and neutral oil vapors may be reheated as desired before they reenter the dephenolizer. Modifications of the process, such as these, may be made without going beyond the scope of this invention, although the preferred method of operating apparatus such as that shown in Fig. 4 comprises supplying the entire heat for both the primary and secondary distillations to the tar in the tar heater 1c and a minimum amount of neutral oils is recovered as such. The residue from the secondary distillation then contains more neutral oils than the residue from an ordinary distillation in which the vaporization of neutral oils is not selectively repressed. The carbolate will ordinarily dissolve some neutral oil, and some neutral oil will be obtained from the vent condenser 23c.

In Fig. 5 provision is made for obtaining tar-acid oils by cooling vapors from the flashing operation or gases and vapors from the secondary distillation before extraction with caustic or other alkaline reagent. The tar is heated in the heater 1d and flashed in the vapor box 2d. Vapors pass through the main 15d to the condenser 50 where they are subjected to regulated cooling and a tar-acid oil, produced by condensation, is drawn off into the storage tank 51. After this regu-

lated cooling the vapors pass through the caustic extractor 4d where tar acids are extracted in the vapor phase. A carbolate formed is collected in the tank 11d. The remaining gases and vapors pass through the main 16d into the secondary still 3d in which the residue from the vapor box 2d is subjected to inert gas distillation.

The gases and vapors from the inert gas distillation in the still 3d pass through the main 19d to the condenser 52 in which tar-acid oils are condensed. These tar-acid oils are drawn off into the storage tank 53. The resulting gases and vapors which still contain vapors or tar acids are then passed through the caustic extractor 5d where tar acids are extracted in the vapor phase and recovered as carbolate in the tank 12d. The remaining gases and vapors pass through the main 20d and a portion of them is combined with vapors from the flashing operation and the combined gases are circulated through the secondary still 3d. A bleed condenser 23d is provided for recovering oil from the remainder of the gases and vapors as previously described.

Of the tar acids contained in the vapors entering the condensers, the higher boiling acids are condensed in the acid oils and the lower boiling tar acids are subsequently recovered as carbolate in the extractors. Fig. 5 shows a condenser preceding each of the caustic extractors. Either of these condensers may be omitted. The vapors from the flashing operation may pass through a condenser and caustic extractor and the inert gases from the secondary still may be subjected to extraction without condensation, or the vapors from the secondary still may be subjected to condensation and then extraction while the vapors from the flashing operation are subjected only to vapor phase extraction without condensation.

Fig. 5 is a somewhat similar to Fig. 1 in that the vapors from both caustic extractors are combined and introduced into the secondary still. Modifications of the apparatus shown in Fig. 4 may include condensers before one or both of the caustic extractors as in Fig. 5. By including a condenser between the vapor box 2c and the caustic extractor 4c of Fig. 4, an oil fraction containing the higher boiling tar acids may be collected from the gases before they enter the caustic extractor 4c. With a condenser in the line 19c to cool the gases from the secondary still before they are combined with the gases in the main 16c, a tar-acid oil may be condensed from these gases and vapors before they are subjected to caustic extraction in the extractor 5c.

Various modifications are possible in which the tar or other hydrocarbon material is flashed in the vapor box and the vapors and residue are separated and the residue is treated for its tar-acid content.

The rate at which gases are circulated through the residue from the first distillation in the inert gas distilling operation will vary depending upon the temperature of the residue treated and the amount of tar acids, etc., recovered. For example, if ordinary coke-oven tar containing three percent of low boiling tar acids is treated and the tar is heated to 175° C. in the tar heater and then flashed in the vapor box so that the vapors pass off through the main 15 at about 150° C. and the residue is drawn off into the secondary still 3 at about 150° C., about 65 percent of the tar acids can be recovered as carbolate in the receivers 11 and 12 without any substantial amount of neutral oils by circulating the gases through the secondary still at a rate of about 300 cubic feet per

gallon of hot tar to be treated. If the gases are to be cooled for the separate recovery of neutral oil or acid oil and all of the heat for the inert gas distillation is to be supplied by the hot residue, 5 the gases will be circulated at a greater rate or the tar should be heated to a higher temperature and the gases circulated at the same rate if the same recovery of tar acids is desired. When tar-acid oils are condensed, part of the acids are 10 covered in those oils and part in the form of carbolite. If gases from the flashing operation are blended with the extracted gases resulting from the inert distillation, then the temperature and amount of the blended gases must be taken into 15 consideration in calculating the rate at which the gases are recirculated. If additional hot gases are added, such as additional steam, etc., the temperature and amount of these added gases must also be given consideration. By cooling the 20 gases and vapors from the inert gas distillation to separately recover one or more neutral-oil or acid-oil fractions, a pitch residue of higher or lower melting point may be produced as desired. By cooling the vapors from the first distillation 25 before introducing them into the secondary still one or more neutral-oil or acid-oil fractions of lower boiling range may be separately recovered.

This application is a continuation in part of our copending application, Serial No. 546,448, filed 30 June 24, 1931.

We claim:

1. The method of treating tar-acid- and neutral-oil-containing liquid hydrocarbon material which comprises heating the hydrocarbon material above its initial boiling point and flashing the 35 heated material to vaporize tar acids therefrom, separately collecting the vapors and heated residue, passing vapors thus collected in contact with an alkaline reagent to absorb the tar acid vapors, 40 vaporizing tar acids from the residue in a current of inert gases and bringing the gases containing tar acid vapors from said residue into contact with an alkaline reagent separate from the aforesaid alkaline reagent whereby tar acid vapors are extracted.

2. The method of treating hydrocarbon material, which comprises heating tar-acid- and neutral-oil-containing liquid hydrocarbon material above its initial boiling point and flashing the 50 heated material to vaporize tar acids therefrom, separately collecting the vapors and heated residue, passing vapors thus collected in contact with an alkaline reagent to absorb the tar acid vapors, vaporizing tar acids from the residue in a current 55 of inert gases by the heat of the residue and then extracting tar acids from the resulting gases and vapors by an alkaline reagent separate from the aforesaid alkaline reagent.

3. The method of treating hydrocarbon material which comprises heating tar-acid- and neutral-oil-containing hydrocarbon material above its initial boiling point and flashing the heated material to vaporize tar acids therefrom, separately collecting the vapors and heated residue, 65 passing vapors thus collected in contact with an alkaline reagent to absorb the tar acid vapors, then vaporizing tar acids from the heated residue in a current of inert gases by the self-contained heat of the residue, extracting tar acids from the 70 resulting gases and vapors by contact with an alkaline reagent separate from the aforesaid alkaline reagent and recycling at least a portion of the remaining vapors of non-acid constituents through the heated residue in admixture with inert gases.

4. The method of treating tar-acid- and neutral-oil-containing hydrocarbon material, which comprises distilling the material at a temperature at which a mixture of vapors of tar acids and neutral oils is evolved therefrom and a hot tar-acid-containing residue remains, separately extracting tar acids from the vapors from this distillation by contact with an alkaline reagent, separately collecting the hot tar-acid-containing residue and bringing at least a portion of the vapors from which tar acids have been extracted by the aforesaid contact with alkaline reagent into direct contact with the residue to aid in the distillation of tar acids therefrom.

5. The method of treating tar, which comprises heating coal tar above its initial boiling point and flashing the heated tar thereby separating vapors of lower boiling tar acid and neutral oil constituents of the tar from the residue, removing the residue from the zone of separation, extracting tar acids from the vapors from the flashing operation by contact with an alkaline reagent while leaving neutral oils in vapor form and using at least a portion of these neutral oil vapors in admixture with inert gases 25 to vaporize tar acids from the residue.

6. The method of treating tar, which comprises heating coal tar above its initial boiling point, flashing the heated tar thereby vaporizing neutral oils and a portion of the tar acids 30 and producing a hot tar-acid-containing residue, separating the vapors from the residue, removing the residue from the zone of separation, extracting tar acids from the vapors by direct contact with an alkaline reagent, passing 35 at least a portion of the vapors of neutral oils in admixture with inert gases through the hot residue thereby distilling tar acids from the residue, extracting tar acids from the resulting 40 gases and vapors and recycling through the hot residue a portion of the resulting neutral oil vapors together with vapors of neutral oils from the flashing operation.

7. The method of treating tar, which comprises heating coal tar above its initial boiling point, flashing the heated tar thereby vaporizing neutral oils and a portion of the tar acids and producing a hot tar-acid-containing residue, separately collecting the residue and the vapors, passing through the residue a mixture 50 of inert gases including neutral oil vapors, blending with the resulting gases and vapors, vapors of neutral oils flashed from the tar in the flashing operation, extracting tar acids from the blended vapors by contact with an alkaline reagent and recycling through the hot residue from the flashing operation at least a portion of the remaining inert gases and vapors of neutral oils to effect the selective vaporization of tar acids therefrom.

8. The method of treating tar, which comprises heating coal tar above its initial boiling point, flashing the heated tar thereby vaporizing neutral oils and a portion of the tar acids and producing a hot tar-acid-containing residue, separately collecting the residue from the vapors, selectively vaporizing tar acids from the hot residue by passing therethrough a mixture 65 of inert gases including neutral oil vapors, extracting tar acids vaporized from said residue by 70 contacting the tar acid vapors with an alkaline reagent, blending at least a portion of the remaining neutral oil vapors with vapors of neutral oil flashed from the tar in the flashing operation and recycling the blended gases through the hot 75

residue from the flashing operation to effect the selective vaporization of tar acids therefrom.

9. The method of treating tar, which comprises heating coal tar above its initial boiling point, flashing the heated tar thereby vaporizing neutral oils and a portion of the tar acids and producing a hot tar-acid-containing residue, separately collecting the residue from the vapors, selectively vaporizing tar acids from the 5 hot residue by passing therethrough a mixture of inert gases including neutral oil vapors, extracting tar acids from the resulting gases and vapors by contact with an alkaline reagent, extracting tar acids from the vapors flashed from 10 the heated tar by contact with an alkaline reagent, and passing vapors of neutral oils resulting from both extractions through the heated residue from the flashing operation in effecting the distillation of tar acids therefrom.

20 10. The method of treating wet tar, which comprises heating it to a sufficient temperature to flash off substantially its entire water content, thereby separating steam and vapors of lower boiling constituents of the tar from the 25 non-volatilized residue, separating the vapors from the hot residue, removing the hot residue from the zone of separation and then passing this steam together with vapors of neutral oils through the residue while still hot to distill tar 30 acids therefrom.

11. The method of treating wet coal tar, which comprises heating it in a continuous still to a temperature sufficient to distill off substantially its entire water content, continuously separating 35 vapors thus produced from the resulting residue, continuously removing residue from the zone of separation, continuously passing at least a portion of the steam thus produced in admixture with neutral oil vapors through the hot residue to distill tar acids therefrom and extracting tar acids from 40 the resulting gases and vapors by contact with an alkaline reagent.

12. The method of treating wet coal tar, which comprises distilling off steam and lower boiling 45 constituents and separating them from the resulting hot residue, removing hot residue from the zone of separation, distilling tar acids from the hot residue in a current of this steam mixed with neutral oil vapors, extracting tar acids from 50 the resulting vapors by contact with an alkaline reagent and blending at least a portion of the resulting neutral oil vapors with the steam for the distillation of tar acids from the residue.

13. The method of treating tar, which comprises heating coal tar above its initial boiling point and flashing the heated tar thereby vaporizing vapors of lower boiling tar acid and neutral oil constituents, separating the vapors from the resulting non-volatilized residue, removing residue 55 from the zone of separation, extracting tar acids from these vapors by contact with an alkaline reagent and employing all of the remaining gases resulting from the flashing in the vaporization of tar acids from the residue.

60 65 14. The method of treating tar, which comprises heating coal tar above its initial boiling point and flashing the heated tar thereby vaporizing vapors of lower boiling tar acid and neutral oil constituents, separating the vapors from the resulting hot residue, removing residue from the zone of separation, extracting tar acids from the vapors by contact with an alkaline reagent and introducing inert gases and neutral oil vapors remaining after this tar-acid extraction directly 70 into intimate contact with the hot residue from 75

the flashing operation together with other inert gases and vapors of neutral oils to vaporize tar acids by the self-contained heat of the residue therefrom.

15. The method of treating tar, which comprises heating coal tar above its initial boiling point, flashing the heated tar thereby vaporizing neutral oils and a part of the tar acids, leaving a tar-acid-containing residue, separating the vapors from the residue, removing residue from the zone of separation, extracting tar acids from the vapors by contact with an alkaline reagent and then cooling them to separate neutral oil therefrom and using at least a portion of the remaining neutral-oil vapors in the distillation of tar acids 10 from the hot residue. 15

16. The method of treating tar, which comprises heating coal tar above its initial boiling point, flashing the heated tar thereby vaporizing neutral oils and a part of the tar acids as vapors 20 leaving a tar-acid-containing residue, separating the vapors from the hot residue, removing residue from the zone of separation, extracting tar acids from the vapors by contact with an alkaline reagent, using at least a portion of the resulting 25 vapors of neutral oils in admixture with inert gases to effect the distillation of tar acids from the hot residue, extracting tar acids from the gases and vapors from this inert gas distillation by contact with an alkaline reagent and cooling them to 30 condense a portion of the resulting neutral oils vapors and blending at least a portion of the resulting neutral oil vapors with neutral oil vapors from the flashing operation, and using them in the distillation of tar acids from the hot residue. 35

17. The method of treating tar, which comprises heating it above its initial boiling point, flashing the tar, separating vapors from the resulting hot residue, removing the residue from the zone of separation, distilling tar acids from 40 the residue in a current of inert gases including neutral-oil vapors, extracting tar acids from the resulting gases and vapors by contact with an alkaline reagent and subjecting them to regulated 45 cooling to separate part but not all of the neutral oil therefrom and recycling at least a portion of the resulting neutral oil vapors through the hot residue, in admixture with inert gases and neutral-oil vapors from the flashing operation.

18. The method of treating tar, which comprises 50 heating it above its initial boiling point to a temperature of about 200° C. or higher, flashing the thus heated tar to vaporize tar acids therefrom, separating vapors from the resulting hot residue, removing residue from the zone of separation, 55 subjecting the separated vapors to a rectification treatment to condense vapors of tar acids while leaving uncondensed vapors of lower boiling tar acids and neutral oils, extracting tar acids from said uncondensed vapors by contact with an alkaline reagent, distilling tar acids from the aforesaid residue in a current of inert gases, extracting tar acids from the resulting gases and vapors by an alkaline reagent and using remaining gases and vapors in the inert gas distillation of the residue. 60

19. The method of treating tar to distill it and obtain an acid oil and a carbolate containing tar acids recovered from the tar, which comprises heating it above its initial boiling point 70 and flashing the heated tar to vaporize a portion of the lower boiling tar acids therefrom, separating vapors from the resulting hot residue, removing residue from the zone of separation, distilling tar acids from the residue in a current 75

of inert gases, cooling the resulting gases and vapors to condense part but not all of the oil vapors and to form an acid oil condensate containing a selective fraction of the higher boiling tar acids in said tar, extracting tar acids from the resulting gases and vapors by an alkaline reagent to obtain a carbolate containing a second selective fraction of the higher boiling tar acids in said tar and using remaining gases and vapors in the inert gas distillation of the residue.

20. The method of treating tar to distill it and obtain an acid oil and a carbolate containing tar acids recovered from the tar, which comprises heating it above its initial boiling point 5 and flashing the heated tar to vaporize a portion of the lower boiling tar acids therefrom, separating vapors from the resulting hot residue, removing residue from the zone of separation, cooling the vapors to condense part but not all 10 of the oil vapors contained therein and to form an acid oil condensate containing a selective fraction of the lower boiling tar acids in said tar, extracting tar acids from the resulting vapors by contact with an alkaline reagent to obtain a carbolate containing a second selective fraction of 15 the lower boiling tar acids in said tar and using at least a part of the remaining vapors in inert gas distillation of the residue.

21. The method of treating tar containing phenols which comprises heating the tar to a temperature sufficient to distill off a portion of the neutral oils and phenols, separating the vapors from the residue and bringing them into intimate contact with an alkaline reagent, thereby extracting phenols from the vapors so as to 20 form a phenolic extract, passing said residue while still at a high temperature into direct contact with an inert vapor stream whereby additional phenols are evaporated from the residue, 25 bringing the resultant vapor stream containing phenols into intimate contact with an alkaline reagent so as to extract phenols therefrom, and collecting the resultant phenolic extract apart from that obtained in the first mentioned phenol 30 extraction step.

22. The method of treating tar containing phenols which comprises heating the tar to a temperature sufficient so that upon subsequent flashing a pitch residue and a vapor distillate 35 at a temperature substantially above 175° C. are obtained, subjecting the resultant vapors to rectification whereby they are partly cooled to a temperature not below about 175° C., passing the 40

rectified vapors into intimate contact with an alkaline reagent so as to remove phenols from the vapors and produce substantially phenol-free vapors, passing the residue from said flashing while yet at a high temperature into direct contact with vapors comprising at least a portion of said phenol-free vapors so as to evaporate phenols from said residue and produce a vapor mixture containing phenols, passing said mixture into intimate contact with an alkaline reagent 5 10 thereby removing phenols from the vapor and producing a second substantially phenol-free vapor and bringing at least a portion of said second substantially phenol-free vapor into contact with said residue to evaporate phenols from the 15 residue and collecting the phenol product from said second-mentioned phenol removal step apart from the phenol product from said first-mentioned phenol removal step.

23. The method of treating hydrocarbon material, which comprises (1) heating tar-acid- and neutral-oil-containing liquid hydrocarbon material to vaporize a portion thereof, (2) separately collecting the vapors and unvaporized residue, (3) vaporizing tar acids from the residue 20 and separately bringing the vapors from (1) and (3) aforesaid into contact with alkaline reagent 25 to extract tar acid vapors and form carbolates.

24. The method of treating tar which comprises heating it above its initial boiling point to a temperature of about 200° C. or higher, flashing the thus heated tar to vaporize tar acids therefrom, separating vapors from the resulting hot residue, removing residue from the zone of separation, subjecting the separated vapors to 30 a rectification treatment by direct contact with a neutral oil condensate to condense vapors of tar acids while leaving uncondensed vapors of lower boiling tar acids and neutral oils, extracting tar acids from said uncondensed vapors by 35 an alkaline reagent, cooling at least a portion of the extracted vapors to condense neutral oils therefrom, employing the neutral oil condensate thus obtained for the aforesaid rectification of vapors from the flashing of heated tar, distilling 40 tar acids from the aforesaid residue in a current of inert gases containing neutral oil vapors, extracting tar acids from the resulting gases and vapors by an alkaline reagent and using remaining gases and vapors in the inert gas distillation of said residue.
